LATCHING MEANS FOR REFRIGERATOR
DOORS

Frank D. Peltier, Indianapolis, Ind., assignor, by
mesne assignments, to Philco Corporation,
Philadelphia, Pa., a corporation of Pennsyl-
vania

Application October 30, 1937, Serial No. 171,812

8 Claims. (Cl. 292—11)

This invention relates generally to refrigerators of the type having inner and outer doors, the outer door forming the principal closure for the food compartment and the inner door serving to divide the food compartment, depthwise, into front and rear chambers with the former situated between the doors when the same are disposed in closed position.

More specifically, the present invention relates to an improved latch organization for the doors of a refrigerator of the described type, and the principal object of the invention is to provide a latch system, including improved operating and manipulating means for the doors of dual door refrigerators, which conduces to a more facile and convenient use thereof. This object is attained by the provision of separate latches for the inner and outer doors and improved means on the outer door for effecting, selectively, the unlatching and opening of the outer door as a single manual operation and without disturbing the inner door, or the concurrent unlatching of both doors by the single manual operation of drawing open the outer door and allowing the inner door to swing open automatically under the action of a spring. This and other objects and advantages will appear from the following description of the presently preferred embodiment of the invention illustrated in the accompanying drawings wherein:

Fig. 1 is a horizontal sectional view of the front portion of a refrigerator showing the main and auxiliary doors in closed position; Fig. 2 is a fragmentary vertical section taken at line 2—2 of Fig. 1; Fig. 3 is a section taken at the line 3—3 of Fig. 2; Fig. 4 is a section taken on the line 4—4 of Fig. 2; Fig. 5 is a view similar to Fig. 2 and showing the operation of the upper door handle; Fig. 6 is a view similar to Fig. 2 and showing the operation of the lower door handle; Fig. 7 is a section taken on the line 7—7 of Fig. 2, and Fig. 8 is a section taken on the line 8—8 of Fig. 2.

In Fig. 1 showing the frontal portion of a dual door refrigerator, numerals 9 denote the opposite side walls of the cabinet structure, such walls terminating forwardly in the jamb pieces 10 and 11. An outer or principal door panel 12 is hinged to the jamb piece 10, and spaced inwardly of door 12 is an auxiliary door 13, likewise hinged to jamb piece 10 by an extended hinge arm 14. The auxiliary or inner door may consist of a shallow pan-like member as shown, having shelves 15 disposed therein and carried thereby. The space behind the inner door 13, indicated at 16,

Fig. 1 is adapted to accommodate the bulk of the food stored in the cabinet and the forward chamber afforded by the hollow inner door provides a more accessible storage space for frequently used foods. The inner door 13 is dimensioned to swing freely into and out of the cabinet through the front opening thereof and its peripheral margins are spaced from the walls of the cabinet so that air can circulate between the chambers.

The inner door 13 is adapted to be held in closed position against the action of a spring device tending to open the same, by a latch assembly mounted on the jamb piece 11. The specific construction of the inner door latch is not of the essence of the present invention except that it should include a latch-releasing element located adjacent the forward face of jamb 11, for manual engagement when the outer door is open, and for engagement by a plunger rod forming an element of the outer door latch, when the outer door is closed. In the present example the inner door latch-release comprises a push-button 17 mounted on one arm 18 of a bell-crank lever, the other arm 19 of which engages one end of a latch lever 20 which normally is urged outwardly by a spring 21 into the path of a keeper portion 22 on the inner door. The push button 17 projects through a front opening in the metal trim which encases the jamb 13, and when depressed, causes its associated bell crank to be swung counter-clockwise (Fig. 1), which pivots latch lever 20 in a clockwise direction and retracts the outwardly projecting portion of the latch lever to release the inner door. When so released, assuming the outer door to be open, a spring mechanism disposed adjacent the hinged side of the inner door urges the same to open position. Such mechanism may, as in the present example, consist of a plunger 23 mounted in a transverse bore in the jamb 10, the plunger being urged against the hinge arm 14 by a compression spring 24.

Secured to the front face of jamb 11 and spaced a short distance below push button 17 is a keeper element 25, such element projecting forwardly from the jamb and (when the outer door is closed) into the latch casing 26 mounted within a marginal portion of the outer door. 45 Mounted on a horizontal pivot pin 27 which extends transversely between opposite side walls of the casing 26 is a latch lever 28, one arm of which terminates in a depending nose portion 30 which is adapted to engage an upwardly directed crook 31 formed on the end of the keeper

25. The other arm 32 of the latch lever 28 projects downwardly and is engaged by the inner end of a horizontal plunger 33 which is supported for endwise movement in an apertured bridge piece 34 extending across the opposite side walls of the latch casing.

The latch lever 28 is adapted to be maintained in either of two positions, shown severally in Figs. 2 and 5, by means of a compression spring 35, the ends of which bear against shoulder portions of an extensible pilot element 36 extending longitudinally through the spring. The upper and lower ends of the pilot element are socketed in recesses 37 and 38 formed in the lower end of latch arm 32 and the bottom wall of the latch casing, respectively. The latch arm 32 and the pilot element 36 may be regarded as the coacting links of a toggle mechanism, the middle joint of which is adapted to pass transversely through an imaginary line connecting opposite end bearings constituted by pivot pin 27 and bearing socket 38. Fig. 2 exhibits the toggle mechanism in one of its conditions of stable equilibrium with spring 35 forcing the latch lever 28 into keeper engaging position. A projection 39 on the latch lever is shown in abutment with a stationary guide piece 40 of the casing which limits the extent of counterclockwise movement of the latch lever under the action of spring 35. The latch lever is adapted to be pivoted clockwise to raise its nose portion 30 out of engagement with keeper 25, by inward movement of plunger 33, the latch lever being maintained in the position shown in Fig. 5, by spring 35 which now tends to turn the latch lever clockwise. Movement of the latch lever in such direction is limited by its engagement with the guide piece 40. The latch lever will remain in the aforesaid position (Fig. 5), corresponding to an open condition of the outer door, until initially displaced by the abutment of its depending arm 32 with keeper 25 when the outer door is closed, such initial displacement being immediately followed by the action of spring 35 which snaps the lever into latching engagement with the keeper element.

The latch casing 26 is ensconced in a suitable recess formed near the side margin of the outer door and is secured in place by a pair of bolts 41 which extend through the door from its inner side for threaded engagement with an escutcheon plate 42 formed on the outer margins of the latch casing. Projecting outwardly from the face of the escutcheon plate 42 are a pair of parallel, spaced walls 43, disposed in vertical planes, and extending across the space between these walls are two pivot pins 44 and 45 which have their ends fixedly secured in opposite outer corner portions of the walls. Mounted on pin 44 for pivotal movement in a vertical plane is a door handle 46, such handle projecting upwardly beyond the top edges of the walls 43.

A downward extension 47 of handle 46 engages an enlargement or head 48 on plunger 33 which plunger is constantly urged outwardly against the handle extension 47 by a spring 49, disposed on the plunger and compressed between the support 34 and plunger head 48. The handle 46 is further provided with an inwardly projecting portion 50 which forms an upper closure for the space between the walls 43, preventing the entry of dirt and dust into the latch mechanism.

Pivots mounted on pin 45 is a door handle 75

51 which may be identical in form to that of handle 46. Handle 51 projects downwardly from the lower horizontal edges of walls 43, is provided with an extension 52 which coacts with plunger head 48, and a transverse projection 53 which forms a bottom closure for the space between the walls 43. With reference to Fig. 7 it will appear that the handle extensions 47 and 50 are complementally disposed in lateral adjacency, each bearing against one-half of the end surface of the plunger head 48. Thus, when either of the handles are rocked outwardly by a manual movement tending to draw the outer door to open position, the plunger 33 will be displaced inwardly to actuate latch lever 28 and disengage it from keeper 25, as has been previously explained.

In addition to its function of unlatching the outer door, the lower handle serves to unlatch the inner door and is operatively related to the inner door latching mechanism through a rod 54. Such rod is slidably supported by the guide piece 40 and is pivotally connected by a pin 55 to the extension 52 of the lower handle so that inward movement of the said extension effects conjoint inward movement of plunger 33 and rod 54. The latch casing is so located that the inner end of rod 54 will register with the push-button 17 when the outer door is closed, and when the rod 54 is displaced inwardly by rocking movement of the lower handle, it abuts and depresses push-button 17 which releases the inner door latch. No operative connection is made between the upper door handle and rod 54, 30 hence the inner door latching mechanism is not affected when the upper handle is utilized to open the outer door. A saddle-shaped sheet metal cover element 56 is mounted over the outwardly projecting walls 43 to give a more finished appearance to the handle assembly and to prevent dirt or the like from entering the mechanism.

The shape, dimensions, and arrangement of latch lever 28, plunger 33, and push rod 54, and the functional association of these parts with the lower door handle 51 is preferably such that unlatching of the inner door precedes the unlatching of the outer door when the lower handle is operated. Sequential unlatching of the several latch mechanisms as aforesaid may be provided for in a number of different ways. For example, plunger 33 may be shortened so that its inner end will be spaced from lever arm 32 and hence will not engage and actuate the lever arm until after plunger rod 54 has actuated push button 17. With reference to Fig. 1, it will be noted that a space exists between the forwardmost extremities of the inner door assembly and the inner surface of the outer door. Accordingly, when the lower handle 51 is used, the same being used only when it is desired to have both doors open together, the inner door latch is released first and by reason of the space aforesaid, the inner door is permitted to swing forwardly under the action of its spring 24 sufficiently to pass the inner door latch lever before that element can re-engage the keeper portion 31. The inner door then follows the outward swinging movement of the outer door.

70 The operation of my improved latching and door operating system, and the convenience attending the use of the described means in connection with a refrigerator cabinet utilizing double doors is believed to be apparent from the foregoing description and drawings. It will be

noted that the means for manipulating the outer door embodies a pair of relatively oppositely directed handles which are lever arms. One of such lever arms is operatively connected only with the outer door latch mechanism, while the other lever arm is operatively connected to both outer and inner door latch mechanisms, hence by selecting the proper lever arm, independent opening of the outer door, or concurrent opening of both doors may be attained. After the outer door has been opened, the push button 17 is readily accessible and may be directly manipulated to effect the opening of the inner door if such is desired.

While I have described my invention with reference to a presently preferred form thereof, I do not wish to be limited to the precise construction herein set forth, as various modifications may be made without departing from the spirit and full intentment of the invention.

I claim:

1. In a latch construction for a plurality of doors for a refrigerator in which the doors are arranged in inner and outer relationship, a latch for each of said doors, the latch for the inner door being normally inaccessible when the outer door is closed; and an operating arrangement carried by the outer door including mechanism whereby both latches may be released for simultaneous opening of both doors and mechanism whereby only the latch for the outer door may be released for opening of the outer door alone, said latch for the inner door including a part accessible and directly manually operable for its release after the outer door has been opened.

2. In a latch construction for a plurality of doors for a refrigerator in which the doors are arranged in inner and outer relationship, a latch for each of said doors, the latch for the inner door being normally inaccessible when the outer door is closed; and an operating arrangement carried by the outer door including a pair of selectively operable latch releasing members, means operatively connecting one of said members to the latch for the outer door to permit opening of the outer door alone upon actuation of said one member, and means operatively connecting the other of said members to the latches for the inner and outer doors to permit simultaneous opening of said doors upon actuation of said other member, said latch for the inner door including a part accessible and directly manually operable for its release after the outer door has been opened.

3. In a latch construction for a plurality of doors for a refrigerator in which the doors are arranged in inner and outer relationship, a latch for each of said doors, the latch for the inner door being normally inaccessible when the outer door is closed; and an operating arrangement carried by the outer door including a pair of pivotally mounted handles, means operatively connecting one of said handles to both latches whereby both latches may be released for simultaneous opening of both doors by said one handle, and means operatively connecting the other of said handles to the latch for the outer door whereby said latch for the outer door may be released for opening of the outer door alone, said latch for the inner door including a part accessible and directly manually operable for its release after the outer door has been opened.

4. In a latch construction for a plurality of doors for a refrigerator in which the doors are arranged in inner and outer relationship for

abutment against proximate portions of a frame, a latch carried by the frame for engagement with a part on the inner door when said door is in closed position; means for releasing said latch and normally inaccessible when the outer door is closed; a second latch carried by the outer door and adapted to engage a part on said frame; and an operating arrangement for both latches carried by the outer door and including a pair of pivotally mounted handles, means operatively connecting one of said handles to both of said latches whereby both latches may be released to permit simultaneous opening of both doors by said one handle, and means operatively connecting the other of said handles to the second latch whereby said latch for the outer door may be released to permit opening of the outer door alone, said latch for the inner door including a part directly manually operable for its release after the outer door has been opened.

5. In a latch construction for a plurality of doors for a refrigerator in which the doors are arranged in inner and outer relationship for abutment against proximate portions of a frame, a latch carried by the frame for engagement with a part on the inner door when said door is in closed position; means for releasing said latch and normally inaccessible when the outer door is closed; a second latch carried by the outer door and adapted to engage a part on said frame; and an operating arrangement for both latches carried by the outer door including a pair of selectively-operable latch-releasing members, means operatively connecting one of said members to the second latch to permit opening of the outer door alone upon actuation of said one member, and means operatively connecting the other of said members to both latches to permit simultaneous opening of said doors upon actuation of said other member, said latch for the inner door including a part accessible and directly manually operable for its release after the outer door has been opened.

6. In a latch construction for a plurality of doors for a refrigerator in which the doors are arranged in inner and outer relationship with respect to a door frame on which said doors are pivotally mounted, a latch for the inner door mounted on the frame and including a push button for releasing said latch, said push button being normally inaccessible when the outer door is closed; and a latching and operating arrangement carried by the outer door including a latch for said outer door, a pair of selectively-operable latch-releasing members, means operatively connecting one of said members to the latch for the outer door to permit opening of the outer door alone upon actuation of said one member, means operatively connecting the other of said members to the latch for the outer door to permit opening of said door upon actuation of said other of said members, and means actuated by said other of said members and engaging the push button of the latch for the inner door to release said latch to permit simultaneous opening of said doors upon actuation of said other of said members, the push button of the latch for the inner door being accessible for direct manual operation to release said latch after the outer door has been opened.

7. In a latch construction for a plurality of

5. In a latch construction for a plurality of doors for a refrigerator in which the doors are arranged in inner and outer relationship, a latch for each of said doors, the latch for the inner

door being normally inaccessible when the outer door is closed; and an operating arrangement carried by the outer door including a first plunger for releasing the latch for the outer door, a second plunger for releasing the latch for the inner door, a pair of pivotally mounted handles both of which are movable into engagement with said first plunger for releasing the latch for the outer door and one of which handles, upon engagement with said first plunger, releases the latch for the outer door to permit opening of said outer door alone and the other of which handles is operatively connected to said second plunger for releasing the latches on both of said doors to permit simultaneous opening of both doors upon actuation of said second plunger by said other of said handles, said latch for the inner door including a part accessible and directly manually operable for its release after the outer door has been opened.

8. In a latch construction for a plurality of doors for a refrigerator in which the doors are arranged in inner and outer relationship for abutment against proximate portions of a frame, a spring-pressed latch lever for the inner door mounted on the frame for engagement with a part on the inner door when said door is in closed position; a push button mounted on the

frame for releasing said spring-pressed latch lever, said push button being normally inaccessible when the outer door is closed; and a latching and operating arrangement carried by the outer door including a spring-pressed latch lever adapted to engage a part on said frame when the outer door is in closed position, a first plunger movable into engagement with the spring-pressed latch lever for the outer door to release said lever, a second plunger movable through said outer door and into engagement with the push button on the frame to release the latch lever for the inner door, and a pair of selectively-operable, latch-releasing members each including means for actuating the first plunger to effect release of the spring-pressed latch lever for the outer door, one of said members also including means for actuating the second plunger to effect release of the spring-pressed latch lever for the inner door, whereby the outer door may be opened independently of the inner door or both of said doors may be released for simultaneous opening thereof, the push button for releasing the spring-pressed latch lever for the inner door being accessible for direct manual operation after the outer door has been opened.

FRANK D. PELTIER.
